Int. Cl. D2—04

U.S. Cl. D2—279

Fig. 1

Fig. 3

FIG. 1 is a side elevational view of a sports shoe showing my new design, the side opposite being substantially similar thereto with the lettering on the foxing continuing as indicated;

FIG. 2 is a front perspective view of the sports shoe; and

FIG. 3 is a rear perspective view of the sports shoe. The characteristic feature of my design resides in the foxing tape portion of the sports shoe design all as shown on the drawing.

I claim:

The ornamental design for a sports shoe, substantially as shown and described.
